UNITED STATES PATENT OFFICE.

ARTHUR McDougall DUCKHAM, OF LONDON, ENGLAND.

CARBONIZING FUEL IN VERTICAL RETORTS.

Application filed May 18, 1922. Serial No. 561,914.

To all whom it may concern:

Be it known that I, ARTHUR McDougall DUCKHAM, a subject of the King of Great Britain, residing in London, England, have 5 invented certain new and useful Improvements Relating to Carbonizing Fuel in Vertical Retorts, of which the following is a specification.

In the operation of carbonizing fuel in 10 vertical retorts steam is frequently introduced into the bottom of the retort for the purpose of reacting with the hot coke to form water-gas. The proportion of steam permissible depends on the temperature of 15 the coke, which temperature has been reached by the carbonization of the mass of coal in the retort, and it has not been found profitable to extend the external heating of the retort to the part containing the coke 20 so as to maintain the temperature of the latter to such a degree that an increased amount of water gas can be made.

By this invention the temperature of the coke at the lower part of a vertical retort is 25 maintained for the purpose in question by introducing oxygen together with the steam, or alternately with the steam. The oxygen may be diluted with a certain proportion of nitrogen as for example 40 per cent of its 30 volume, but the quantity of nitrogen thus introduced must not exceed that which, when mixed with the gas produced by the carbonizing process as a whole, would bring the percentage of nitrogen to the maximum 35 percentage permissible with respect to the calorific value of the gas. By adopting this mode of internally heating the coke in the lower part of the retort, not only is the temperature better maintained, so that the output 40 of water-gas, and hence of total gas, is increased, but the cost of externally heating the lower part of the retort is saved.

The oxygen is preferably admitted together with the steam and the accompanying drawings show in Figs. 1 and 2 in vertical sections in planes at right angles to each other a retort provided with suitable inlets for the purpose.

The figures represent a retort *a* heated by combustion occurring in flues *b* in which the heating gases pass downwards to the waste gas flues *c*; below these latter flues the setting contains on each side of the retort a U-shaped pipe *d* closed at one end and having that limb which is nearer to the retort 55 perforated to permit gaseous fluid to issue through nozzles *e* into the retort. A mixture of steam and oxygen is passed into the open end of the U-tube and becomes preheated by the heat of the waste gas flues before 60 it enters the retort.

Having thus fully described the nature of the said invention and the best means I know for carrying the same into practical effect, I claim:—

1. A process of carbonizing fuel which consists in placing the fuel into externally heated vertical retorts, introducing steam into the bottom of the retort, and introducing oxygen mixed with nitrogen, the nitrogen being used in quantities of not more than 40 per cent of the volume of the oxygen into the lower part of the retort in such a manner that it comes in contact with the hot coke and maintains the temperature of 78 the latter at the degree necessary for the production of water-gas from the steam.

2. A process of carbonizing fuel which consists in introducing the fuel into externally heated vertical retorts, and introducing steam and oxygen mixed with nitrogen, the nitrogen being used in quantities of not more than 40 per cent of the volume of the mixture into the lower part of the retort.

3. A process of carbonizing fuel which consists in introducing the fuel into vertical retorts, and passing oxygen mixed with nitrogen into the retort, the nitrogen being used in quantities of not more than 40 per cent of the volume of the oxygen and steam alternately into the lower part of the retort.

In testimony whereof I have signed my name to this specification.

ARTHUR McDougall DUCKHAM.
